BLOCK FOR SECTIONAL GRINDING WHEELS

Frank C. Penny, Trumbull, Conn., assignor to
The Bridgeport Safety Emery Wheel Company, Inc., Stratford, Conn., a corporation of Connecticut

Application October 16, 1934, Serial No. 748,458

6 Claims. (Cl. 51—209)

This invention relates to new and useful improvement in blocks for sectional grinding wheels of the type shown in patents to Hyde, Numbers 1,133,475 and 1,589,855 of March 30, 1915, and 5 June 22, 1926, respectively.

An object of the invention is to provide an improved construction of shoe for the blocks of a sectional grinding wheel.

More specific objects of the invention are to 10 provide a shoe for a block of a sectional grinding wheel and which shoe is light in weight and comprises a minimum of metal and may be manufactured at low cost whereby it need not be returned to the factory for refilling when the abrasive 15 block is worn down.

Additional objects are to provide a shoe as indicated and which is so constructed as to be firmly attached to the block to which it is moulded, and which does not materially detract from the cross 20 section of the block in its shearing zone, and which provides means whereby a marker plug may be moulded directly into the abrasive block on its inner end.

Other objects and advantages will become apparent from a consideration of the following detailed description taken in connection with the accompanying drawing wherein a satisfactory embodiment of the invention is shown. However, it will be understood that the invention is not limited to the details disclosed but includes all such variations and modifications as fall within the spirit of the invention and the scope of the appended claims.

In the drawing:

Fig. 1 is a front elevational view showing a portion of a sectional grinding wheel;

Fig. 2 is a sectional view taken substantially along the plane of the line 2—2 of Fig. 1;

Fig. 3 is a front elevational view, on an enlarged scale, showing an abrasive block and shoe, with part of the abrasive block broken away;

Fig. 4 is a sectional view taken substantially along the plane of the line 4—4 of Fig. 3;

Fig. 5 is a rear elevational view of the shoe alone, on the scale of Fig. 3; and

Fig. 6 is a detail sectional view taken substantially along the plane of the line 6—6 of Fig. 3.

Referring in detail to the drawing a portion of a sectional grinding wheel is shown at 10 and 30 the same comprises a support including a carrying disc 11 having a hub 12 for attachment to a shaft, a portion of which is shown at 13, and said disc 11 has on one face thereof a pair of spaced flanges 14 and 15 between which grinding blocks 16 are mounted. The space between the two

flanges is divided into a plurality of pockets by transversely extending divisional webs or members 17 which are secured in place in any suitable manner. The wheel 10 is assembled with two grinding blocks 16 in each pocket, and such blocks 5 are preferably shaped in cross section substantially as best shown in Fig. 1 although not necessarily so. Blocks 16 are secured or clamped in position by means of tapered wedges 18 in the spaces between two adjacent blocks and the wedges 10 are adjusted by screws 19 passed through the inner flange 14 of the support and such screws are locked in adjusted position as by nuts 20. These wedges clamp the blocks against the flange 15 and webs 17.

Each grinding block 16 includes an abrasive block or portion 21 and a metal shoe 22 secured to the inner end of the abrasive portion as by being moulded thereto. Shoe 22 is in the form of an open frame-like structure including a body portion 23 having inner and outer peripheral edges. An outer flange 24 extends forwardly from the outer edge of the body 23 and such flange is tapered on its inner side 25 whereby it is thinnest at its forward or free edge. A flange 26 extends forwardly from the inner peripheral edge of the body 23 and this flange 26 in addition to extending forwardly inclines inwardly of the shoe or in a direction away from the outer flange 24. On its inner peripheral edge 27 the body and flange 26 30 have a continuous taper from the forward or free edge of the flange 26 through to the rear surface of the body.

As here shown, a rib 28 extends transversely across the body and such rib may be centrally 35 enlarged and in such enlarged portion provided with a tapped opening 29. The inner flange 26 of the body extends along the opposite sides of rib 28, and where such flange is on the rib it is designated 30 and it is further noted that the 40 continuous taper 27 is carried out on the portion 30 of the flange whereon the tapered surface is designated 31. From this it will be understood that looking into the front of the shoe 22 as in Fig. 3 the opposed surfaces of the flanges 24 and 26 incline away from one another and that the flange portions 30 of the rib 28 incline away from the rib.

When the abrasive material 21 is moulded to the shoe 22 to form a complete block 16 the said 50 material enters into the spaces between the flanges 24 and 26 and also enters the openings 32 and 33 through the frame-like body of the shoe. It will be understood that the rib 28 divides the space through the shoe into two parts whereby the two 55

openings 32 and 33 are formed. The abrasive material entering the openings 32 and 33 in the body of the shoe passes to the rear of the flange 26 and completely fills the openings, entering 5 under the inclined surfaces 27 which as above stated extend from the forward or free edges of the flanges 26 to the rear surface of the body of the shoe. From Fig. 4 it will be clear that the material thus interlocks with the shoe in such 10 a manner that when the material is set and hardened the shoe and the abrasive material are bound or moulded together with the shoe dovetailed to the abrasive material by means of the flange 26 and the inclined rear surface portions 27. 15 When the block 16 is being moulded a marker plug 34 may be moulded into the rear end of the abrasive material. This is accomplished simply by disposing the plug in one or the other of the openings 32 and 33 with the plug facing toward 20 the rear of the shoe 22. That is as the block is molded with the shoe in a horizontal position with surface 23 resting on the bottom of the flask the disc 34 is merely placed face down on this bottom within one of the openings 32 or 33 25 and then the plastic abrasive material molded onto the shoe and the disc. In this way a plug carrying marks indicating the grade and grain size of the abrasive material is moulded into the completed abrasive block so that the block is 30 permanently identified, the marker plug being so located as not to be worn away as the block is used but is easily visible. The threaded opening 29 of each shoe receives an adjusting screw 35 and the abrasive portion 21 of the block is 35 provided with an opening 36 accommodating the screw. The screw of each block passes through an opening 37 in the disc 11 and has a flange 38 engaging the inner wall of the disc whereby movement of the screw in one direction is limited. 40 On the opposite side of the disc is a lock-plate 39 which is forked at one end so as to be passed into an annular groove 40 in the screw 35 whereby to prevent withdrawal of the screw. Plate 39 is secured to the support as by a screw 41 which 45 must, of course, be loosened before the plate may be shifted. If no adjusting screw is used the tapped opening 29 may be omitted.

The manner of adjusting the blocks 16 is described in my patents above referred to and forms 50 no particular part of the present invention. The present invention relates to the shoe 22 and the abrasive block molded to it and it will be noted that since the shoe is in the form of an open frame it includes but a minimum of metal and is 55 light in weight. As the inner flange 26, which may be continuous or may be interrupted as by the rib 28, enters into the abrasive material 21 at an angle or so as to form a dove-tail connection, with portions of the abrasive material at both 60 the front and rear sides of the flange, it will be appreciated that the material 21 and shoe 22 are securely locked together.

Shoe 22 may be a casting or a pressed or forged shoe, and when cast may be moulded without the 65 use of cores. This is true since the pattern may be easily withdrawn from the sand in which either of its faces is moulded, that is, on the rear face of the shoe there is but the one continuous incline 27 and on the forward face of the shoe 70 the opposed surfaces of the flanges 24 and 26 taper or incline away from one another toward their free edges. It can therefore be molded with straight draws on the pattern. Since the shoes include but little metal and since they may be 75 cheaply moulded without the use of cores they

represent very little loss when thrown away after the abrasive block is worn down. These shoes may be manufactured at such prices that it is not necessary that they be returned to a factory for refilling after the original abrasive block to 5 which they were moulded has been worn away.

The shearing zone or section in the blocks 16 would be at the forward edge of the outer flange 24 of the shoe. That is, the shearing section is the cross section of the abrasive block at the 10 edges of flanges 24 so it will be seen it is practically the full cross section of the block. In the present shoe or with the present shoe this shoe and the abrasive block are firmly secured together without having any inwardly extending 15 projection on the free edge portion of the outer flange 24 of the shoe. In fact, this flange is thinnest at its free or forward edge so that the cross section of the abrasive portion 21 is not materially reduced in its shearing zone or section, which 20 zone, as above explained, is at the free edge of the flange 24. Therefore, with the present construction the abrasive portion of the block may be worn down further or a greater part of said portion of the block may be used, with little danger 25 of the block shearing off or breaking. This fact coupled with the fact that the shoes 22 contain but a minimum of metal and may be easily moulded without the use of cores makes it reasonable to discard the shoe of a block when the 30 abrasive is worn down, and not return the block to the factory for refilling. Further, as above explained, with the present shoe a marker plug such as 54 may be moulded into the inner end of the abrasive block or in that portion of the 35 abrasive block extending through the rear face of the shoe, so that it will be readily visible to an operator or other workman positioning the blocks on a support, and it is not necessary to mark the shoe or cut or mold these marks in the abrasive 40 itself.

Having thus set forth the nature of my invention, what I claim is:

1. In a block for a sectional grinding wheel, a metal shoe, a block of abrasive material moulded onto said shoe, said shoe comprising a frame-like structure open at both the front and back sides thereof comprising a body having inner peripheral edges about the opening in the back and outer peripheral edges about the outside 50 of the frame, inner and outer forwardly projecting flanges on said body at said edges, said inner flange inclining inwardly of the body away from the outer flange and having its rear wall inclined outwardly toward the rear surface of the 55 body.

2. In a shoe for a block of a sectional grinding wheel, a frame-like structure open at the front and rear comprising a body having inner peripheral edges about the opening through the back 60 and outer peripheral edges about the outside of the frame, a rib extending across the body and connecting a pair of portions thereof, said rib having a tapped opening therein, a forwardly projecting flange at the outer edge of said body, 65 a flange at the inner edge of the body and at each side of said rib and inclining forwardly of the body and away from the outer flange, and the wall on the inner edge of said body being outwardly inclined from the free edge of said inner 70 flange to the rear surface of the body.

3. In a shoe for a block of a sectional grinding wheel, a frame-like structure open at the front and rear comprising a body having inner peripheral edges about the opening through the 75

back and outer peripheral edges about the outside of the frame, a forwardly extending flange at the inner edge of said body, said flange inclining in a direction away from the outer edge 5 of the body, and the rear wall of said flange being inclined outwardly from its free edge.

4. In a shoe for a block of a sectional grinding wheel, a frame-like structure comprising a body 10 open at the front and rear having inner and outer peripheral edges, inner and outer forwardly projecting flanges on said body at said edges, said inner flange inclining away from the outer flange, the inner surface of said outer flange being inclined outwardly whereby the flange is thinnest at its forward edge, and the rear wall of 15 said inner flange being inclined rearwardly in the opposite direction.

5. In a shoe for a block of a sectional grinding wheel, a frame-like structure comprising a body open at the front and rear having inner and outer peripheral edges, inner and outer for- 20

wardly projecting flanges on said body at said edges, said inner flange inclining away from the outer flange, the inner surface of said outer flange inclined outwardly whereby it is thinnest at its forward edge, said inner flange extending about 5 the inner edge of said body and having a rear wall inclined outwardly and rearwardly from its inner edge.

6. In a shoe for a block of a sectional grinding wheel, a frame-like structure comprising a body 10 open at the front and rear having inner and outer peripheral edges, a rib extending across the body and connecting a pair of portions thereof, said rib having a tapped opening therethrough, a forwardly projecting flange at the outer edge of said 15 body, a flange at the inner edge of the body extending forwardly and inclining away from the outer flange, with its rear wall inclined outwardly and extending to the rear surface of the body.
